CLAIM

The ornamental design for a grinding jig, as shown and
described.

DESCRIPTION

FIG. 1 is a front view of the invention.

FIG. 2 is a top plan view of the invention.

FIG. 3 is a first end view of the invention.

FIG. 4 is a second end view of the invention.

FIG. 5 is a back view of the invention.

FIG. 6 is a bottom plan view of the invention.

FIG. 7 is a front perspective view of the invention; and,
FIG. 8 is a rear perspective view of the invention.
